INVENTOR:
Chas. R. Watson.
Chas. M. Chapman,
ATTORNEY

UNITED STATES PATENT OFFICE.

CHARLES R. WATSON, OF NEW YORK, N. Y.; SALLIE ABELL WATSON EXECUTRIX OF
SAID CHARLES R. WATSON, DECEASED.

UNDERGARMENT.

1,376,381.

Specification of Letters Patent. Patented Apr. 26, 1921.

Application filed February 7, 1920. Serial No. 356,825.

To all whom it may concern:

Be it known that I, CHARLES R. WATSON, a citizen of the United States, residing in the borough of Manhattan, city, county, and 5 State of New York, have invented a new and useful Improvement in Undergarments, of which the following is a description.

This invention has reference to undergarments and, particularly, to "combination" 10 undergarments for men's wear.

Among the objects of my invention may be noted the following: to provide a combination garment made of woven and knitted material, the knitted material being 15 incorporated and applied so as to provide a garment the back of which, below the waistline, is unusually elastic; to provide a combination garment with an elastic back below the waistline adapted to yield to a considerable degree of use; to provide an undergarment formed of a combination of woven and knitted fabric which gives to the garment great durability, strength and 20 wearing quality, and, at the same time, enables the garment to be made without any seat openings and gives to the seat great elasticity.

With the above objects in view and others which will be detailed during the course of 30 this description, my invention consists in the parts, features, elements and combinations thereof hereinafter described and claimed.

In order that my invention may be clearly 35 understood, I have provided drawings wherein:

Figure 1 is a view in front elevation of a combination undergarment having my invention applied thereto; and

40 Fig. 2 is a view in back elevation of the garment shown in Fig. 1.

Referring to the drawings, the numeral 1 indicates the front body of the garment which, preferably, is made all in one piece, 45 2 is the back upper body of the garment which, preferably, is made all in one piece, and 3 are the back members of the lower portion of the garment constituting the seat and legs, or the parts below the waistline, 50 or approximately below the waistline. The front portion 1 of the garment is made entirely of woven fabric, as is also the upper back portion 2 of the garment. The two lower back portions 3 of the garment are 55 made entirely of knitted fabric. The nu-

meral 4 indicates the neck opening, 5 the armhole openings, and 6 the placket or front opening, which opening it will be noted extends clear from the neck opening 4 to the crotch 7. The knitted members 3, of which the lower back or seat of the garment and legs are composed, is seamed longitudinally and centrally of the garment, as at 8, and also seamed, as at 9, at the sides to the woven material. The pieces 3 of knitted material are also seamed approximately at the waistline 10 to the back section 2 of woven material, and the latter is likewise seamed at its opposite sides to the front section 1 of woven material, as indicated at 11, said seams being in continuity with the seams 9. The knitted material 3 of the two leg portions are seamed, as at 12, to the front section 1, and is also seamed to said front section at the crotch which is 75 reinforced and strengthened by stitching or an added strip, as may be desired, and indicated at 13. The armholes 5 and neck opening 4 are hemmed and finished in usual manner, as indicated by the lines of stitching 80 thereabout.

The total width of the members 3 of knitted material is considerably greater below the waistline than the total width of the woven material at the front of the garment, the fullness being indicated in Fig. 2 by 14 and in Fig. 1 by 15, where it is shown quite full in the crotch. According to my invention, the body of the garment below the waistline is quite full, and especially in 90 those portions which encompass the legs of the wearer. The object of this is to give to the wearer perfect ease of movement as a primary characteristic. As a secondary characteristic, the knitted material 3, of which the lower back of the garment is composed, is not only inherently quite elastic, so that it may be stretched laterally extraordinarily; but, the said material is made quite full, as shown at 14, to give still 100 greater extensibility to the leg portions so that the latter may be easily and adequately drawn aside for use. By making the garment in the main or two-thirds, approximately, of woven material, its durability is greatly increased, since it can withstand twists, strains and laundering and other usual wear and tear, which the knitted material cannot inherently stand. On the other hand, by making the seat and lower 110

back of the garment of knitted material, and quite full as shown, it is given great elasticity and is capable of being quite effectively drawn aside for use. Moreover, 5 the back of the garment can readily be replaced when worn without destroying the rest of the garment. Thus, added longevity is given the garment making it more desirable, economical and satisfactory.

10 The front opening of the garment may be closed in any usual manner, as by buttons and buttonholes, indicated generally at 16; and it is a feature of my invention that there is but one opening in the garment 15 which extends from the crotch, or approximately from the crotch, to the neck opening.

Having thus described my invention, what I claim and desire to secure by Letters Patent is:

20 1. A combination garment formed of woven fabric throughout its entire front and approximately half of its back, and having approximately the lower half of its back formed of knitted material, said garment 25 being narrow at the top and very wide at the bottom and increasing in width gradually from top to bottom, and having neck, arm and leg openings and only one opening in the body thereof beginning at the crotch 30 and terminating at the neck opening in the front.

2. A combination garment formed of woven material throughout its front, and a single piece of woven material throughout 35 approximately half of its back, and having the lower half of its back formed of knitted material, and considerably wider than the corresponding front portion so as to produce a back seat and leg fullness, and said 40 garment having neck, arm and leg openings and only one opening in the body thereof beginning at the crotch and terminating at the neck opening in the front.

3. A combination garment formed of woven material throughout its front, and a 45 single piece of woven material throughout approximately half its back, and having the lower half of its back formed of two pieces of knitted material joined together centrally lengthwise of the garment and to the back 50 and front woven portions, respectively, the said lower half of the back of the garment being made quite full, and said garment having neck, arm and leg openings and only one opening in the body thereof beginning 55 at the crotch and terminating at the neck opening in the front.

4. A combination garment having its entire front and approximately half of its upper back formed of woven material, and the 60 lower half of its back formed of knitted material, the total width of the latter being considerably greater than the total width of the woven material of which the front is composed, whereby fullness of the garment 65 in the seat, crotch and legs is provided for, and said garment having neck, arm and leg openings and only one opening in the body thereof beginning at the crotch and terminating at the neck opening in the front, 70 substantially as described.

5. A combination garment formed to provide neck, arm and leg openings, the latter being abnormally wide, and to be narrow at the neck and of gradually increasing 75 width from top to bottom, said garment being composed of a front of woven, comparatively inelastic material, a back, the upper half of which is of woven material and the lower half of which is of elastic mate- 80 rial, the latter being considerably wider, from side to side, than the front lower half of the garment so as to provide a fullness for seat and legs to be drawn aside for use.

CHARLES R. WATSON.
